UNITED STATES PATENT OFFICE

ERIK J. MORDT, OF EVANSTON, ILLINOIS

DESIGN FOR A COMBINED TOY PISTOL HOLSTER AND BELT

Application filed June 5, 1931. Serial No. 40,090. Term of patent 14 years.

To all whom it may concern:

Be it known that I, ERIK J. MORDT, a citizen of the United States, and resident of Evanston, in the county of Cook and State of Illinois, have invented a new, original, and ornamental Design for Combined Toy Pistol Holster and Belt, of which the following is a specification, reference being had to the accompanying drawings, forming part thereof.

I claim:

The ornamental design for a combined toy pistol holster and belt, as shown.

ERIK J. MORDT.
